UNITED STATES PATENT OFFICE.

JOHN P. CONNELL, OF KENSINGTON, CONNECTICUT.

IMPROVEMENT IN STEAM, WATER, AND GAS COCKS.

Specification forming part of Letters Patent No. 147,240, dated February 10, 1874; application filed December 30, 1872.

To all whom it may concern:

Be it known that I, JOHN P. CONNELL, of Kensington, Hartford county, Connecticut, have invented an Improved Globe-Valve, of which the following is a specification, reference being had to the accompanying drawings, where—

Figure 1 is a side view of the whole valve. Fig. 2 is a view of the same in central vertical longitudinal section.

The letter *a* indicates the globular part of the valve; *b*, the entrance-pipe; and *c*, the exit-pipe. *d* is the partition in which is the valve-seat *d'*, facing toward the entrance-pipe. *e* is the valve proper, and *f* the valve-stem, having on its outer end the operating-wheel *g*. There is a screw-thread, *f'*, on the stem *f*, taking into the nut or collar *i*, resting in a corresponding recess in the neck *h*, and held from turning by the pin *i'* projecting from the nut and into a corresponding recess in the neck. The letter *g'* indicates the stuffing-box, screwing upon the neck *h*.

It will be observed that the neck *h* is solid, except the hole for the valve-stem, and can therefore be cast in one piece with the globe *a* and pipes *b* *c*. Not only this, but the pressure of the fluid coming in at the pipe *b* tends to always close the valve into its seat and make it tight; and a valve thus made with solid neck *h* is not liable to explode by having the plug-screw driven out.

I claim as my invention—

The neck *h*, solid except a hole for the valve-stem, and made upon and in one piece with the body *a*, in combination with the threaded valve-stem *f*, the nut held from turning, and the stuffing-box *g'*, all constructed, arranged, and designed for operation and use, substantially as described.

Dated October 13, 1873.

JOHN P. CONNELL.
